LOOSE HEADSTOCK OF A LATHE

Johan George Kronouer, Eindhoven, Netherlands,
assignor, by mesne assignments, to Hartford
National Bank and Trust Company, Hartford,
Conn., as trustee

Application May 3, 1946, Serial No. 667,036
In the Netherlands March 18, 1942

Section 1, Public Law 690, August 8, 1946
Patent expires March 18, 1962

4 Claims. (Cl. 82—31)

1

This invention relates to a loose stock member of the kind used in a lathe and more particularly to the attachment of this stock, which is movable along the lathe bed, to the latter.

It is well-known to provide the loose stock with a separate part available in the bed of the lathe, which part is movable relatively to the stock. By means of a lever having an eccentric this loose part may be moved relatively to the said loose stock in such manner that this stock such as the tail-stock is clamped to the bed of the lathe. After loosening this attachment the motion of the stock over the bed yet remains difficult, particularly with heavy head-stocks.

The present invention has for its purpose to avoid this difficulty and is characterized in that at least one roller secured in a movable manner to the stock is located between two slide faces in the bed and in one position bears on one of the slide faces so that the loose stock is clamped to the bed, whereas in another position of this roller it engages the other slide face and lifts the loose stock from the bed of the lathe.

The construction according to the invention yields the advantage that the said roller serves on the one hand for clamping the loose stock and on the other hand supports the loose stock on the bed of the lathe. By means of this roller the loose stock is allowed to roll over the bed so that it can be easily shifted.

The loose stock is preferably equipped with four of such rollers which are provided pairwise on either side of this stock. In this case the loose stock can travel as a whole along the bed.

The invention will be more fully explained by reference to the accompanying drawing representing, by way of example, one form of construction thereof.

Figure 1 is a cross-sectional view of a loose lathe stock member according to my invention taken along the line 1—1 of Figure 2 looking in the direction indicated by the arrows.

Figure 2 is a side view in elevation of the means of Figure 1 taken along the line 2—2 of Figure 1.

In the drawing the reference number 10 designates the bed which is provided on either side with a slot 11 whose upper and bottom face 23 and 24 respectively are realized to constitute slide faces. Furthermore the bed comprises a flat portion 19 and a V-shaped gutter 21 to which the loose head stock can be clamped. This V-shaped gutter 21 serves to fix the correct position of the loose stock in a direction at right angles to the bed.

2

The loose stock member such as a tail-stock member 17 comprises two ribs 15 and 16 which are located at some distance from the side wall of the stock and integrally connected to the said side-walls by means of the portion 17—A (see Figure 2). Each of these ribs is perforated at two points and carries a shaft 14. This shaft 14 has an eccentrically located cylindrical end 13 about which a roller 12 of hard steel is freely rotatable. This shaft 14 is rigidly connected to the lever 22 which is movable in a space between the said ribs and the side wall of the loose stock member. The shafts 14 can be rotated by means of both these levers 22 at the same time by means of the connecting bar 22—A which results in that the eccentric part 13 is moved upward and downward so that the hard steel rollers 12 engage either the bottom slide faces 24 or the upper slide faces 23. In the first mentioned case the bottom sides 18 and 20 respectively of the ribs 15 and 16 are lifted from the bed. The weight of the stock 17 is transmitted solely through the rollers 12 to the bed so that the loose stock can travel over the bed by means of the rollers 12. By displacing the levers 22 the rollers 12 are pushed against the slide faces 23 as a result of which the flat slide face 18 is at the same time pushed against the face 19 of the bed and the V-shaped shoulder 20 is pushed into the V-shaped groove 21. The stock is now clamped to the bed.

What I claim is:

1. Stock apparatus for a lathe, which comprises a stock member having side-wall portions and perforated rib portions in spaced-apart relation, a bed-like support member having a V-shaped gutter-like slot and square slide slots parallel to each other and to the said wall portions and rib portions, lever members, shaft members attached to said levers at the ends thereof and mounted for rotation in the said perforations and having eccentrically connected end portions, and roller members mounted for rotation on the said eccentric end portions, said rollers bearing on the top and bottom surfaces of the said square slots according to the extent and direction of the actuation of said levers.

2. Stock apparatus for a lathe, which comprises a stock member having side-wall portions and perforated rib portions in spaced-apart relation, a bed-like support member having a V-shaped gutter-like slot and square slide slots parallel to each other and to the said wall portions and said rib portions, lever members, shaft members attached to said levers at the ends thereof and mounted for rotation in the said per-

forations and having eccentrically connected end portions, and roller members mounted for rotation on the said eccentric end portions, said rollers bearing on the top and bottom surfaces of the said square slots to couple and uncouple the said stock member and said support member according to the extent and direction of the actuation of said levers.

3. Stock apparatus for a lathe, which comprises a stock member having apertured side-wall portions and perforated rib portions in spaced-apart relation, a bed-like support member having a raised central portion, a V-shaped gutter-like slot and square slide slots formed in the said central portion parallel to each other and to the said wall portions and said rib portions, lever members, shaft members attached to said levers at the ends thereof and mounted for rotation in the said perforations and having eccentrically connected end portions, and roller members mounted for rotation on the said eccentric end portions, said rollers bearing on the top and bottom surfaces of the said square slots according to the extent and direction of the selective actuation of said levers.

4. Stock apparatus for a lathe, which comprises a stock member having side-wall portions

and perforated rib portions in spaced-apart relation, a bed-like support member having a V-shaped gutter-like slot and square slide slots parallel to each other and to the said wall portions and said rib portions, at least four lever members, shaft members attached to said levers at the ends thereof and mounted for rotation in the said perforations and having eccentrically connected end portions, and at least four roller members mounted pairwise one behind the other for rotation on the said eccentric end portions, said rollers bearing on the top and bottom surfaces of the said square slots according to the extent and direction of the actuation of said levers.
